CLAIM

The ornamental design for a container dome, as shown and described.

DESCRIPTION

FIG. 1 is a perspective view of a container dome embodying our new design;

FIG. 2 is an elevational view of the container dome of FIG. 1;

FIG. 3 is an elevational view of the container dome of FIG. 2 rotated clockwise 30° about its central vertical axis;

FIG. 4 is a top plan view of the container dome of FIG. 1; and,

FIG. 5 is a bottom plan view of the container dome of FIG. 1.

The broken line showing of the spout in FIGS. 1-3 and of the multi-faceted panels in FIGS. 1-5 is for illustrative purposes only and forms no part of the claimed design.
